MEANS FOR CLOSING ELEVATOR DOORS

Chester K. Wilson, Cleveland, Ohio, assignor to
 The Haughton Elevator Company, Toledo,
 Ohio, a corporation of Ohio

Application June 25, 1947, Serial No. 756,952

2 Claims. (Cl. 187—31)

1

This invention relates to means for closing elevator doors. More specifically, it relates to means for automatically completing the closing of a nearly closed freight elevator door when the elevator starting switch is closed.

In closing elevator doors, especially doors of freight elevators, it has been customary to employ an electric motor controlled by a manually closed switch that automatically opens instantly when the manual closing pressure is released, so that the door can be stopped instantly if danger develops of injury to a person having a member in the path of the closing door. It is customary, also, to provide such doors with an interlock which prevents the elevator from starting unless the door is completely closed. This interlock is required by building codes which specify the maximum gap which may be left in the door and still allow the elevator to operate.

In some cases the operator releases pressure upon the door-closing switch when the door is nearly closed but still leaves a gap wider than that specified so that the interlock prevents operation of the motor. The present invention is of utility under such circumstances. The invention comprises an automatic door-closing device operated upon the closing of the elevator starting switch which will complete closing of a nearly closed door, permitting operation of the interlock for elevator starting, but which will not operate if the door is open to a degree dangerous for automatic closing.

One embodiment of the invention is illustrated in the accompanying drawings, forming a part of this specification, and in which Fig. 1 is a diagrammatic illustration of a wiring arrangement for the invention, with the door closed sufficiently to allow immediate starting of the elevator; Fig. 2 is a view of the door slightly open, so that the invention will function before the elevator starts; Fig. 3 is a section on the line 3—3 of Fig. 2, and Fig. 4 is a section on the line 4—4 of Fig. 1.

In the embodiment illustrated in the drawings, the door consists of the lower half 10 and upper half 11. Chains 12 from the upper half pass over pulleys 13 and are attached to rods 14 extending up from the lower half, thus counterbalancing the two halves for opening and closing movement. Such movement of the door halves may be produced by actuating a motor 15 connected by a reduction gear, (not shown) to a lever 16 provided with a pin 17 movable horizontally in a slot 18 in the upper half.

Motor 15 is reversible, and is actuated in door-closing direction when switch 19 is closed and

2

in door-opening direction when switch 20 is closed. Switch 19 is closed by energizing coil 21, one end of which is permanently connected through wire 22 to power line 23. The other end of the coil 21 is connected by line 24 through switch 25 to line 26 running through switch 27 to line 28, which in turn is connected to line 29 by switch 30. Line 29 is connected by switch 31 to line 32 which is a branch of line 24. Leading from line 26 is a line 33 connected by a branch 34 to power line 35.

Switch 25 is of the push button type which is automatically opened when closing pressure is removed. It will be seen that motor 15 will be actuated in closing direction whenever switch 25 is closed, and also when all of switches 27, 30 and 31 are closed.

Switch 27 is connected to a retiring cam 36 which operates a lever 37 for unlocking the door, 20 when projected, and when withdrawn allows the lever to lock the door provided catch 38 can project beneath the lower half of the door. The cam is normally projected, and is retired by energizing a coil 39.

Switch 30 is normally closed, but is opened upon the energizing of coil 40 one end of which is connected permanently by wire 41 to power line 23 and the other end of which is connected through a switch 42 to power line 35. Switch 42 is open as long as the door is unlocked, but is closed when catch 38 moves to a position under the lower half of the door. Switch 31 is normally opened, but is closed when a cam 43 on the lower half of the door engages a lever 44 and closes the switch against the pressure of spring 45.

The elevator motor is energized in the up direction by closing switch 46 and in the down direction by closing switch 47, provided switch 48, 40 interposed in the power line to the starting relays, is closed. Closing either of the starting switches completes the circuit through coil 39 and retires cam 36. If the door is closed so that catch 38 can move beneath and lock the door, switch 42 is closed, energizing coil 40, opening switch 30 and closing switch 48. The closing of switch 48 energizes the relay for starting the elevator motor.

If the door is not closed sufficiently to be locked 50 when switch 46 is closed, catch 38 engages the door and prevents the closing of switch 42 and this in turn prevents the closing of switch 48 and the starting of the elevator motor. However, if the parts are in the position in which they are 55 shown in Figs. 2 and 3, with astragal 49 on the

upper half closing the gap between the halves so as to avoid danger of anyone having an arm, hand or fingers between the door halves, switch 30 will remain closed, switch 31 will be closed by engagement of members 43 and 44, and when switch 27 is closed as a result of closing switch 46, motor 15 will be energized in the door-closing direction. As soon as the door is closed sufficiently to be locked, switch 42 is closed, energizing coil 48, opening switch 30 and de-energizing motor 15 and simultaneously closing switch 48 and starting the elevator motor.

If an attempt is made to start the elevator when the door is open too widely for cam 43 to operate lever 44 and close switch 31, the closing motor is not energized, and the elevator cannot be started until the door is closed by manual closing of switch 25.

It will be readily understood that cam 43 is made short enough so that there is no automatic closing of the door when it is open too far for safe automatic closing, but when so nearly closed that further automatic closing is safe, actuation of the starting switch automatically completes the closing necessary for locking, and so the slightly incomplete initial closing is overcome with a minimum of delay and with no additional movement by the operator.

By this invention, the operation of freight elevators is simplified and expedited without decreasing the safety of operation.

While but one door is shown, it will be readily understood that the automatic means for completing the closing may be added to the interlock for each door of the elevator shaft.

While only one arrangement has been illustrated and described, various changes may be made while retaining the essential features set forth in the appended claims.

What I claim is:

1. In an elevator installation comprising a door, a motor for closing the door, a manually operable switch for starting the door motor, an elevator motor, a starting switch for the elevator motor, and an interlock preventing the starting of the elevator motor when the door is incompletely closed, means automatically energizing the door motor for completing the closing of the door when the starting switch for the elevator motor is actuated if, and only if, the door is nearly closed.

2. In an elevator installation comprising a door, a motor for closing the door, a manually operable switch for starting the door motor, an elevator motor, a starting switch for the elevator motor, and an interlock preventing the starting of the elevator motor when the door is incompletely closed, a circuit for energizing the door motor in the closing direction by-passing said manually operable switch and comprising a switch closed by the closing of the starting switch for the elevator motor, a switch open when the door is widely open and automatically closed when the door is closed, so nearly that its closing may be safely completed automatically, and a switch automatically opened by the operation of the interlock when the door is completely closed.

C. K. WILSON.
